UNITED STATES PATENT OFFICE

JOHN W. HOOLEY, OF LARCHMONT, NEW YORK

MATCH PACKAGE

Application filed August 24, 1931. Serial No. 559,013.

This invention relates to the packaging of matches, and has particular reference to those packages consisting of inner tray-shaped receptacles enclosed in slidable members, the latter having coatings of material over which the heads of the matches are drawn to ignite them. So-called safety matches are almost universally so packaged.

When such a package as just referred to is mounted on the match-box block of a wall bracket such as employed in the smoking rooms of Pullman cars, or on the match-block of a table ash tray, it is customary to so mount the package that the outer member is slid down onto the block so that the inner member or tray and the matches therein project above the open-ended slide, and the matches are then partially exposed for accessibility. When a match is removed and ignited by drawing it up or down along one of the igniting surfaces of the slide which is vertical, it frequently happens that the entire package is displaced from the block or equivalent of the holder, and the matches are then scattered about. This most frequently occurs when a match is "struck" by drawing it upwardly along the vertical igniting surface, it being natural to increase the pressure of the match against said surface as the match is so moved. And even if the pressure is not so increased, there is nothing to act against the upper end of the package to resist lateral movement thereof. And if the striking movement is in a downward direction, the first pressure against the upper end of the side of the package is liable to displace it. In either case, the match-striking operation is liable to displace the entire package, and cause a scattering of the matches.

One of the objects of my invention is to provide packages of matches of the type referred to but which present igniting surfaces that are so inclined as to materially reduce liability of the package being displaced from its support when a match is being ignited by drawing it along the side surface of the package.

Another object is to provide packages of matches which are not likely to be taken away from their supports by kleptomaniacs.

With said objects in view, and others hereinafter explained, the invention consists in the construction and combination of parts substantially as hereinafter described and claimed.

Of the accompanying drawing,

Figures 1 and 2 are perspective views of my improved packages mounted on the blocks of a common type of ash tray.

Figure 3 is a front elevation of one of my improved match packages, a portion of the front wall of the slide member being broken out.

Figure 4 is a side elevation of the same.

Figures 5 and 6 are elevations illustrating other forms of the match packages.

Similar reference characters indicate similar parts or features in all of the views.

Referring first to Figures 1, 3 and 4, the tray member 10, for holding the matches 11, and the slide member 12 which encloses the tray and matches, are both of tapering form from end to end, the matches being closely packed in the tray with their larger ends or heads in the wider end thereof. The outer surfaces of the side walls of the slide are coated with material to coat with the heads of the matches to ignite the latter when the heads thereof are drawn along one of said coated surfaces as is usual with so-called safety matches. Such coating is indicated by the stippled areas of the slide.

In Figures 1, 2, 3 and 4, the side walls of the slide and tray are illustrated as equally inclined upwardly and inwardly, but I do not limit myself thereto. For instance, as illustrated in Figure 3 only one side wall may be so inclined, and as illustrated in Figure 6 the side walls may be parallel for part of their lengths and tapered inwardly the rest of their lengths.

Figures 1 and 2 illustrate a common form of ash tray having a block-shaped portion 14 over which it is customary to fit the lower end of the slide of a safety-match box, with the lower end of the inner member or tray bearing on the top of such block. This is one of the ordinary ways of mounting a box of safety matches. But when one of my improved packages is mounted in the same way,

as illustrated by Figure 1, both side walls which present match-igniting surfaces are inclined so that if a match is struck by drawing its head in an upward direction over the coating as is usually done, the pressure along the upper end of the box is far less than is usually exerted when the coated surface is vertical, and therefore there is much less liability of knocking the box off from the block. If the match-striking movement is in a downward direction there is, of course, no tendency to separate the box from its support when the closing pressure reaches the lower end of the box.

I have referred to the support for the package as an ash tray having a block member, but the term block is intended to be a generic one applicable to any part of a support capable of having the slide 12 fitted thereon.

Owing to the fact that the tapered shapes of the tray and slide limit the degree to which the smaller end of the tray can be caused to project from the slide, the matches are not easily accessible if the package is left in the condition illustrated in Figure 1, and therefore the porter, or club attendant, or some one else, is induced to break away the upper end wall of the tray, or an upper portion of the front wall of the slide, or both as illustrated in Figure 2, in order to render the matches easily removable singly. This results in so mutilating the box as to render it incapable of retaining the matches if the whole is removed from the stand or holder, and therefore there is little or no inducement for anyone to effect such removal with the object of securing a free box of matches.

Another advantage obtained by my improved packages, is the reduction of space required for the storage or transportation of a quantity of them. This is because they can be packed with their larger ends alternating with their smaller ends side by side. The packages now in common use are of uniform size from end to end and therefore, since the larger ends of the matches, the heads thereof, are always at one end of the tray, the opposite ends of the matches are unnecessarily loose.

Another advantage of my improved box or package is that only the larger end of the box can be slipped onto the standard block of the usual ash tray, and the heads of the matches are always in said larger end. Consequently, a box of the matches can not be carelessly so mounted on the block that the heads of the matches will be exposed liable to be accidentally ignited as sometimes happens with the safety matches in a box of the common type.

A somewhat minor advantage due to the form of my improved packages, although of considerable importance when considered in connection with the fact that any millions of safety-match boxes are annually made and

used, is that packages such as illustrated and described herein require less material than those which are at present in common use.

While I have chiefly referred to the invention as related to the packaging of so-called safety matches, it is to be understood that the matches may be of other kinds which merely require that the outer surfaces of the boxes are coated with sand or other suitable material against which the heads of the matches are to be drawn.

Having now described my invention, I claim:—

1. A box comprising a tray and a tapered shell enclosing the tray, one end of the tray substantially fitting the larger end of the shell, the taper of the shell being such as to prevent drawing the tray entirely through the smaller end of the shell.

2. A box comprising a tapered tray and a tapered shell enclosing the tray, the said tray and shell substantially fitting each other, the degree of taper being such as to prevent drawing the tray entirely through the smaller end of the shell.

3. A box comprising a tapered tray and a tapered shell enclosing the tray, the said tray and shell substantially fitting each other, the degree of taper being such as to prevent drawing the tray entirely through the smaller end of the shell, the shell having a side coating of match-igniting material.

4. The combination with a holder having a block member, of a box comprising a tray and a tapered shell enclosing the tray, one end of the tray substantially fitting the larger end of the shell, the taper of the shell being such as to prevent drawing the tray entirely through the smaller end of the shell, the larger end of the shell being mounted on said block member.

In testimony whereof I have affixed my signature.

JOHN W. HOOLEY.
